BOX HANDLE STRUCTURE

John W. McIlwraith and Edward L. Miller, New Castle, Pa., assignors to Associated Box Corporation

Application September 25, 1942, Serial No. 459,695

8 Claims. (Cl. 16—125)

This invention relates to a handle structure for containers and more particularly the form thereof and the force distributing connection therebetween.

At present, chiefly for export shipment to the Orient and other localities not having mechanical facilities for handling and transporting boxed heavy loads, great difficulty is experienced in providing for such boxes or containers handle structures capable of manual application without failure.

It has been discovered the heavy loads (containers), if provided with one or more loop-like handles at each end, can be readily handled and transported by two or more porters, one or more being at each end of the load. If a single handle is provided at each end and centrally positioned, a long pole can be passed through same and one or more porters at each end thereof thus carry said load. If two handles are provided at each end, a pair of poles may be provided and two, four or more porters can easily carry same and the included load.

Since the containers are usually heavily loaded, as with guns, ammunition and other war materials and supplies, the problem is to provide a sufficiently strong, relatively inexpensive handle structure and one capable of anchorage so that it will not fail or become detached from the container.

The present invention, therefore, has as its primary objective the provision of such a handle structure meeting the aforesaid requirements.

The chief feature of the present invention consists in applying to a container a cotton webbing strap, preferably in loop handle form and anchoring same to the container in such a manner that "pull out" separation does not occur under normal use.

Another chief feature of the present invention is to provide a load distributing type anchorage whereby the effective load strain upon any localized portion of the strap is less than the strap shearing capacity, although the total load exceeds same, and the strap anchorage proper can receive and distribute the load without strap shearing.

Other objects and features of the invention will be set forth more fully hereinafter.

The full nature of the invention will be understood from the accompanying drawing and the following description and claims:

In the drawing:

Fig. 1 is a perspective view of a corner of one form of cleated container, the top and bottom

being omitted, and to which a handle embodying the invention has been applied.

Fig. 2 is a perspective view of one form of strap anchor plate.

Fig. 3 is a transverse sectional view through the handle anchoring portion and associated parts.

Fig. 4 is a perspective view of a modified form of anchor plate.

Fig. 5 is a view similar to Fig. 3 of the invention including the plate shown in Fig. 4.

Fig. 6 is a diagrammatic sketch of the invention shown in Figure 5, full lines indicating the initial and dotted lines indicating the final or load applied positions of the anchor plate.

Fig. 7 is a perspective of a further modified clip.

Fig. 8 is a longitudinal section similar to Figs. 3 and 5 and illustrates the use of the plate shown in Fig. 7.

In Figs. 1 and 3 of the drawing 10 indicates the side, 11 the end and 13 an end cleat, of one form of cleated box. Herein nails (or screws) 14 secure the cleat to the end 11 and nails (or screws) 15 secure the sides to the ends and adjacent cleats. Herein the end cleat on and in its end confronting face 12 is provided with a channel or recess 16, which opens on a side face of the cleat as at 17.

While herein a container, as illustrated, would be provided at each end with inclined recesses as singularly illustrated, but in reversed relation, that is directed towards each other, the container may be of full cleated character and the top cleat may be provided with a downwardly opening recess medianly positioned between the ends of that cleat. In this case the strap loop, hereinafter to be described would normally hang downwardly from the top cleat and lie in the chamber formed by the peripheral cleat arrangement. When in use the strap would be held upwardly and doubtless bear upon the outer face of the cleat.

In Fig. 1, there is illustrated a loop form of strap, 18 indicating the loop portion, and 19 the adjacent lapping ends of such strap, see Fig. 3. These two ends are seated in the groove or recess 16 and in the present form of the invention a distributing plate 20 is interposed therebetween.

Such a plate, see Fig. 2, has an elongated body portion 20, is substantially, but not necessarily, of strap width and at one transverse edge is provided with oppositely directed teeth 21. The teeth engage in the confronting faces of the

strap ends as shown in Fig. 3. The strap is of multiply cotton webbing and may be similar to that utilized for army trouser belts. Such webbing of an inch width and one-eighth inch thickness has a capacity of from 700 to 1000 pounds tensile strength before stretch failure occurs. Its shearing resistance, that is resistance to cutting action, is exceptionally less as evidenced by the fact that such webbing can readily be cut by a hand shears or pocket knife using ordinary hand pressure.

To utilize such material having such divergent values, as a handle, presents the problem of strap anchorage wherein the shearing effect, incident to load strain application, is substantially eliminated, or otherwise expressed, the load strain, instead of being localized and applied as a shearing strain, is distributed and handle failure, under actual tests at the Pittsburgh Testing Laboratory, occurs by shearing action under a load strain of from 700 to 1000 pounds, or almost that of the tensile failure value of the strap or webbing.

Failure, or "pull-out" accordingly with this invention, instead of occurring at twenty to fifty pounds or even a hundred pounds, will not occur until the load applied is 700 or more pounds.

Experiments, accordingly, have demonstrated that handle "pull-out" failure occurs approximately at tensile strength failure.

To further understand these actions, reference is had to Figs. 1 and 3. Therein it is noted one of the nails 14 passes through the cleat, the strap ends, the anchor plate, the cleat recess and extends into the box end. If the anchor plate were omitted, load on the loop 18 would cause the nail 14 to cut the ends 19 like a knife. The load failing value accordingly would be very low. Now, with the nail passing through the plate as at 22, and load applied to loop 18, said load is taken by the teeth 21 and transmitted to plate 20 and by it at 22 to nail 14. Now, before "pull-out" can occur the nail 14 must shear the metal plate 20 at 22.

It is by reason of this anchor arrangement that handle failure and tensile strength failure are of approximately the same value. Actual experiments show that in many cases the strap ends and the plate bodily move outwardly a slight amount and nail 14 has formed therein a laterally directed U-shaped portion before actual "pull-out" or failure can occur. Of course, when so tested for failure the nail 14 also shears the strap ends the amount that the ends and plate move before failure actually occurs, but such shearing is incidental and of no consequence in the present invention, whereas if the plate were omitted and nail 14 passed only through such strap ends, such shearing would be highly critical.

It is not essential that nail 14 pass through plate 20 for the edge 23 may abut same and the same distributing effect be obtained. In this connection also it is to be observed that the teeth 21 are connected by arc-shaped formations 24 to the body of the plate 20. Also, it is to be observed, see Fig. 2, that the outside teeth are directed outwardly, as well as toward the adjacent web. When strain is applied to the strap, the teeth dig into and imbed into the adjacent faces of the ends 19. Since initially the plate 20 may be considered immovable, the teeth 21 tend to further imbed in the ends 19 and then bend backward toward edge 23.

When the teeth so bend, the plate holding of

the ends ceases and all load then is concentrated on the strap ends where the nail 14 passes therethrough, shearing occurs and failure follows. The explanation is given solely to indicate how failure can occur when the handle is tested for failure.

It is quite apparent that with four handles a container having a total load of twenty-four hundred pounds can be readily transported by 10 manual labor, and as shown in Fig. 1, by the use of poles 30, this load can be distributed among two, four, eight or more porters, so no porter will be overloaded.

Reference will now be had to Figs. 4 to 6 inclusive. In these figures 210 indicates the sides, 211 the ends, 213 the cleat, 216 the groove or recess therein, 218 the strap forming the loop and having ends 219 seated in said groove and projecting from opening 217. Nails 214 secure the cleat to the end and nails 215 secure the side to the box end and cleat.

Referring now to Fig. 4, plate 220 includes angular portion 224 with teeth 221 at one end. The other end of said plate including abutment portion 223 with teeth 222. As shown in Fig. 5 this plate is positioned between the strap lapping ends 219 and teeth 221 and 220 at opposite ends of said plate imbed in said ends.

Referring to Fig. 6, it will be observed that one 30 angular portion bears against nail 214, see also Fig. 5, and as shown therein the oppositely directed teeth imbed in the strap ends.

When load is applied to the handle, the plate 220 engages nail 214 and stops further handle 35 movement until the nail is bent U-shaped in the groove, or the angular portion bends back at right angles. This, of course, means the teeth on that portion move to transverse position. At the same time the foregoing occurs, the strain 40 on the other strap tends to move the other angular portion and adjacent teeth transversely. Failure occurs when either set or both sets of teeth move beyond the perpendicular toward the other set, or towards each other. Of course, nail 45 214 does shear the strap ends 219 to the degree necessary to move the handle to cause the nail and angular portion contact and bearing.

Fig. 6 illustrates the load sustaining position by dotted lines, the full lines indicating the initial 50 assembled position prior to load application.

The foregoing embodiments illustrate the abutment and pierced contact types, the singular toothed end and opposite toothed end types, and the oppositely directed teeth in one end, or at 55 opposite end types. Other types of anchor plates have been tried. Likewise, there is nothing to prevent piercing plate 220 by nail 214, or having a special nail in lieu of cleat retaining nail 214 or 14.

60 Reference will now be had to Figs. 7 and 8 wherein a different form of anchor clip and plate and modified form of anchorage is illustrated in that two clips are necessary. Each clip is U-shaped in end elevation and each end 65 424 has its edge provided with strap engaging teeth 421. Herein the teeth extend in the same direction from the body portion 420, see Fig. 7.

In Fig. 8, the invention is illustrated and 70 since one clip can imbed its teeth into only one strap end 419, two clips, oppositely positioned, are provided. These clips abut each other and one abuts the retainer, the nail 414 extending from cleat 413 to end 411 and through groove 416 and strap ends 419.

The operation is substantially the same as pre-

viously described. Load strain on the handle causes the clips to engage each other and the one closest to nail 414 to engage said nail. When these engagements are effected, the teeth 421 imbed in the strap ends 419, as before described. Failure only can occur when the load is so great that the substantially perpendicular teeth 421 bend appreciably and angularly away from the nail or direction of the load strain, as shown by dotted lines Y in Fig. 8. Such tooth bending occurs when the teeth 421 shear the strap ends 419.

While the invention has been illustrated and described in great detail in the drawings and foregoing description, the same is to be considered as illustrative and not restrictive in character.

The several modifications described herein as well as others which will readily suggest themselves to persons skilled in this art, all are considered to be within the broad scope of the invention, reference being had to the appended claims.

The invention claimed is:

1. A strap handle anchorage for a container having a fabric strap receiving recess, including in combination a fabric strap having an end seated in the recess, a retaining member and an anchor plate means of appreciable width juxtaposed to the retaining member and adjacent the strap end and recess seated, said anchor means including a plurality of strap engaging teeth seatable in the strap for local distribution of total strain when the member and means have engagement under strap applied strain.

2. An anchorage as defined by claim 1 characterized by the container including a wall portion and a cleat portion with confronting faces, the recess being positioned therebetween, the retaining member passing through the recess seated strap portion and the anchor means and through one portion and into the other portion.

3. An anchorage for a fabric strap having considerable tensile strength in a longitudinal direction compared to its shearing or cutting resistance in the same direction, including in combination a strap retaining member passing through the same, and an anchor member having operative engagement with said retaining member when the strap is under appreciable tensile strain, said anchor member having a plurality of transversely offset teeth embeddable in the strap when the latter is under appreciable tensile strain, said teeth distributing the total load strain, when the anchor member and retaining member are engaged, to localized portions of the strap, to reduce the localized load at any point in the anchored portion to a value below the unit shearing or cutting force value of the strap to prevent pull-out.

4. In a container having a cleat thereon with a recess in the container confronting face thereof, the recess having an opening at one end, the combination of a fabric strap member having a free end inserted in the recess and a hand engageable portion projecting therefrom, a retainer extending through the cleat, recess and into the container and assisting in cleat retention upon the container, and strap anchoring means seat-

able in the recess and operatively associated with the retainer for retention in the recess thereby and having strap engaging teeth for distributing the strain localized upon the retainer across the width of the strap.

5. In a container having a cleat thereon with a recess in the container confronting face thereof, the recess having an opening at one end, the combination of a fabric strap member having a free end inserted in the recess and a hand engageable portion projecting therefrom, a retainer extending through the cleat, recess and into the container and assisting in cleat retention upon the container, and strap anchoring means seatable in the recess and operatively associated with the retainer for retention in the recess thereby and having a plurality of longitudinally spaced series of strap engaging teeth, each series having a plurality of transversely arranged teeth, said teeth distributing the strain localized upon the retainer across the width of the strap and longitudinally of strap.

6. A container as defined by claim 4 characterized by the anchor means including a plurality of toothed members, opposite ends of each toothed member having its teeth similarly directed.

7. In a container having a cleat thereon with a recess in the container confronting face thereof, the recess having an opening at one end and opening toward the center of box, the combination of a loop handle forming fabric strap having opposed layers at the handle end seated in the recess, strap anchoring means interposed between the layers and nested in the recess therewith and having teeth at its inner end and oppositely directed for embedment into the adjacent face of the strap upon load strain application thereto, and cleat retaining means extending therethrough the strap and across the recess and into the container, engageable by the strap anchor means for receiving the strap applied load to the retaining means.

8. A strap handle anchorage for a container having a recess for receiving a fabric strap therein, including in combination a fabric strap arranged in loop formation and having both ends lapping each other and seated in the container recess, a retaining member carried by the container and passing through the recess seated ends of the strap and extending across the recess, and an anchor plate means of appreciable width and length and juxtaposed to the retaining member and seated in the recess and between the strap lapping ends and including a plurality of oppositely directed strap engaging teeth seatable in the lapping ends when load strain is applied to the strap, said plate means having operative engagement with the member when the load strain is applied to the strap, said plate means by tooth end-strap and plate means-member engagements distributing the total load strain in the strap to the teeth engaged portions thereof whereby the local strain at any tooth engaged portion is well below the limit of strap failure at that portion.
